COMBINED MOBILE PEDESTAL MOUNT AND HOUSING FOR A COIN-OPERATED TELEVISION RECEIVER

Walter Leroy Abell, Jr., 6045 Round Hill Court, Columbus, Ga. 31904, and Harold C. Hogencamp, Rte. 2, Box 486, Smiths, Ala. 36867

Filed Aug. 31, 1970, Ser. No. 24,765

Term of patent 3½ years

Int. Cl. D14—03

U.S. Cl. D56—4

FIG.1

FIG.2

FIG. 1 is a left side, top and front perspective view of a combined mobile pedestal mount and housing for a coin-operated television receiver, showing our new design; and

FIG. 2 is a right side, top and rear perspective view thereof.

A portion of FIG. 1 is diagonally lined to indicate transparency.

We claim:

The ornamental design for a combined mobile pedestal mount and housing for a coin-operated television receiver, substantially as shown and described.
